UNITED STATES PATENT OFFICE.

SILAS M. FORD, OF ST. PAUL, MINNESOTA; CLARA P. FORD, EXECUTRIX OF SAID SILAS M. FORD, DECEASED, ASSIGNOR TO CLARA P. FORD.

LATH BOARD AND METHOD OF MAKING THE SAME.

Application filed November 27, 1922. Serial No. 603,655.

One object of my invention is to provide a lath board formed of paper or other suitable material corrugated into dove-tailed shape plait, the material of which is impregnated 5 from both sides with a water-proofing compound, fire-proofing compound or stiffening compound of some type, but having the central portion unimpregnated.

Another object is to provide a lath board 10 of the class described, the outer surfaces of which are coated or enameled.

Another object is to provide a lath board 15 of the class described having reinforcing wires therein which are coated with a water-proofing material.

Another object is to provide in a lath board of the class described, having reinforcing wires therein, means for making a substantially rigid connection between the 20 wires and material composing the lath board.

Another object is to provide a method for 25 making a lath board of the class described with the central portion thereof having high insulating qualities and all exposed portions thereof water-proofed.

With these and incidental objects in view, 30 the invention consists of certain novel features of construction and combinations of parts, the essential elements of which are hereinafter described with reference to the drawing which accompanies and forms a part of this specification.

In the drawing, Figure 1 is a perspective view of a lath board embodying my invention; Figure 2 is an enlarged fragmentary detail of the same, showing the outer surfaces of the sheet impregnated and the inner portion unimpregnated with a water-proofing compound and Fig. 3 is an enlarged section taken longitudinally through one of the reinforcing wires.

As shown in the drawing, the lath board 45 consists of a sheet of paper, felt or of other suitable material preferably corrugated into a substantially dove-tailed formation with lath like faces 1 on one side thereof and intermediate depressions 2 between the lath like faces and supporting faces 3 on the other side of the lath board, the latter faces being 50 narrower than the lath like faces as described in my co-pending application of even date, entitled, "Lath board."

Reinforcing flat wire or ribbons 4 are 55 threaded thru the webs 5 connecting the lath like faces and the supporting faces as de-

scribed in said application aforesaid and also in various patents heretofore issued to me.

It will be noted that where the reinforcing wires pierce the webs, there is an accumulation of the water-proofing compound 60 6 (Fig. 3) which flows up around the wire forming a heavy firm fillet which not only cements the wire firmly to the web but also stiffens and reinforces the wire in its connection with the web so the same stiffness 65 of completed board can be obtained with a thin wire cemented in this manner that could be obtained by a much thicker wire that merely pierced the web without having a fillet built up around the aperture. 70

In the past it has been common in the manufacture of lath board of this class to use a sheet of material which has been impregnated with a bituminous compound 75 such as asphalt and to corrugate the material so impregnated into the desired shape.

Where the lath board has been reinforced with metal, it has been customary to use wire or ribbon uncoated and hence subject to deterioration if left exposed to the 80 weather.

It is also well known that paper or felt which has high heat insulating qualities loses a great deal of its heat insulating 85 qualities when impregnated with water-proofing or fire resisting compound.

Inasmuch as the heat insulating qualities on any material of this class depends upon the amount of air trapped in and held by the fibers of the material between the outer 90 surfaces thereof, it is evident that if the sheet is impregnated with the waterproofing compound, this air will practically all be expelled from the sheet and heat can be 95 more readily transferred through the waterproofing substance which completely fills the sheet than through the dead air spaces in the unimpregnated sheet.

It is also evident that steel wire will rust 100 when exposed to moisture and that in storage, shipment and ordinary usage, the reinforcing wire will be subject to exposure and consequently to deterioration.

In my present invention, I prefer to form 105 an unimpregnated sheet of material into a dove-tailed shape, thread reinforcing wires through the webs and then dip the entire board with its reinforcing wire into a water-proofing compound.

The board is left in the compound suf- 110

sufficiently long to thoroughly cover the insulating wires and all exposed surfaces of the board but not long enough for the compound to impregnate the board. The result is a 5 board formed of a sheet of material which has a center of unimpregnated material, both sides of which are formed of the same material but impregnated with waterproofing compound.

10 In other words, the completed board is very much the same as if it was made of two sheets of impregnated material with a sheet of unimpregnated material therebetween but with the fibers of all three sheets 15 intimately joined together. Moreover the reinforcing wires are entirely covered with water-proofing material and are closely cemented to the webs where they pass through and any holes or imperfections in 20 the sheet which might have crept in during the process of manufacture will be filled by the dipping operation.

While I have described my invention and 25 illustrated it in one particular style and method, I do not wish it understood that I limit myself to this particular embodiment as it is evident the invention may be varied in many ways within the scope of the following claims:

30 1. A lath board comprising a sheet of suitable material having the outer surfaces thereof coated with a water-proofing compound and the inner portion thereof unimpregnated with said compound, said sheet 35 being formed into a substantially dove-tailed

shaped formation having oppositely disposed lath like faces with intermediate depressions therebetween and webs connecting said faces and a plurality of reinforcing wires threaded through said webs between 40 said faces, said wires being covered with a water-proofing compound.

2. The method of making lath board comprising the corrugating of a sheet of suitable material of high insulating qualities into 45 the desired shape, passing reinforcing wires through said material parallel to the outer faces of the completed board, then dipping said reinforcing sheet into water-proofing compound sufficiently long to coat the wires 50 and outer surfaces of the sheet with said compound and cement them together, but leaving a substantial portion of the sheet between the faces unimpregnated with said compound.

3. In a lathboard, the combination of a sheet of corrugated material, a reinforcing wire threading said material and fillets of a dipping compound surrounding said wire 55 where it pierces said material.

4. A lathboard comprising the combination with a sheet of suitable material formed into substantially dove-tailed shaped corrugations having oppositely disposed lath-like faces with connecting webs therebetween, of a plurality of reinforcing wires piercing said webs, and fillets of an adhesive material connecting said wires to said webs where said webs are pierced by said wires.

SILAS M. FORD.
